UNITED STATES PATENT OFFICE.

JOHN ALBRECHT, OF KEWAUNEE, WISCONSIN.

NAIL-FEEDING MECHANISM FOR BOX-NAILING MACHINES.

Application filed August 29, 1921. Serial No. 496,468.

To all whom it may concern:

Be it known that I, JOHN ALBRECHT, a citizen of the United States, and resident of Kewaunee, in the county of Kewaunee, 5 and State of Wisconsin, have invented new and useful Improvements in Nail-Feeding Mechanism for Box-Nailing Machines, of which the following is a description, reference being had to the accompanying drawings, which are a part of this specification.

This invention relates to improvements in nail feeding mechanisms for box nailing machines more particularly adapted for forming boxes and other like articles.

15 An object of the invention is to provide a feeding mechanism for a nailing machine in which any number of nail feeds may be easily stopped when desired without interfering with the operation of the remaining nail feeds.

20 A further object of the invention is to provide a nailing machine particularly adapted for high speed work in which the nail feeding mechanism of the machine can only feed one nail at a time to its driving hammer.

25 A further object of the invention is to provide a nailing machine which may be adjusted to automatically drive a different number of nails on different side edge portions of a box fed thereto.

30 A further object of the invention is to provide a nailing machine which may be adjusted to alternately drive a different number of nails at each stroke of the driving hammer.

35 A further object of the invention is to provide a nailing machine which may be adjusted to automatically alternately drive a predetermined number of nails or which may be manually controlled to drive different numbers of nails.

40 A further object of the invention is to provide a nailing machine which is of simple construction, is strong and durable and is well adapted for the purpose described.

45 With the above and other objects in view the invention consists of the improved nailing machine and its parts and combinations 50 as set forth in the claims, and all equivalents thereof.

In the accompanying drawings in which the same reference characters indicate the same parts in all of the views:

55 Fig. 1 is a side view of the improved nailing machine;

Fig. 2 is a front view thereof;

Fig. 3 is a vertical sectional detail view, 60 on a larger scale, of the nail feeding portion of the machine;

Fig. 4 is a top view of the machine, taken on a larger scale;

Fig. 5 is a rear view of the lower portion 65 of the machine taken on a larger scale; and

Fig. 6 is a sectional detail view taken on line 6—6 of Fig. 4.

Referring to the drawings the numeral 8 indicates the base portion of the machine and 9 the standard which is formed with vertically extending guide rails 10 upon 70 which is slidably mounted a box holding platform or carriage 11. Said carriage is adjusted vertically in any manner desired by means of the vertical screw 12 which has a yielding nut connection 13 with the carriage. The standard is also provided with a forwardly extending frame portion 14, a forwardly extending nail chuck receiving arm 15 and a reciprocating arm 16 carrying 75 hammers 17.

A drive shaft 18 extending transversely of and journaled in the lower portion of the standard 9 is provided with a driving wheel 19 and a gear wheel 20 which is in mesh with a gear 21 mounted on an intermediate 80 counter shaft 22 also journaled in the standard. Said counter shaft 22 at its opposite end carries a gear 23 which is in mesh with a gear 24 mounted on a front counter shaft 25. The intermediate counter shaft 22 also 85 carries an eccentric 26 engaged by a connecting rod 27 which at its upper end is connected to and reciprocates the arm 16 carrying the hammers. The gear 21 is loose on the shaft 22 and is provided with a clutch 90 28 of ordinary construction which locks the gear to said shaft. A foot lever 29 mounted on the base portion 8 of the machine controls the operation of the clutch so that when 95 pressed downwardly by the operator the clutch will connect the gear 21 to the shaft 22 and turn the same one complete revolution.

A nail receptacle 30 hinged at its forward end 30' to the upper end of the frame portion 14 is connected by a rod 31 to a ball wrist pin 32 projecting eccentrically from a worm gear 33 which is mounted on a short shaft 34. Said shaft is journaled in the frame and extends above and at right angles 100 to the shaft 18, and the gear 33 of said shaft 105 is in mesh with and rotated by a worm 34 110

mounted on the shaft 18. Said construction oscillates the receptacle 30 and causes the nails 35 to feed downwardly from said receptacle and through the nail slots 36 of the 5 frame 14. Segmental nail feeding members 37 journaled on the frame 14 are formed with peripheral nail recesses 38 which are in register with the nail slots 36 when in a normal position of rest, and are of a size to just 10 receive the shank portion of the nails. The segmental members 37 are formed with forwardly projecting arms 37' which are provided with laterally extending adjustable screw stop members 38 which bear against 15 stop rollers 39 mounted on a reciprocal bar 40. Said bar 40 is reciprocated by means of a cam arm 41 which is rigidly mounted on and extends upwardly from the reciprocal arm 16. The cam arm extends through an 20 end portion of the reciprocal bar and its angular offset portion 41' moves said bar back and forth. Coiled springs 42 connected to peripheral portions of the segmental members and to portions of the frame 14 exert 25 a tendency to swing the notched portions of the segmental members to the left, with reference to Fig. 4, and into register with tubular conveyors 43. As the adjusting screws 38 of the segmental member 37 bear 30 against the stop rollers 39 the reciprocation of the bar 40 and the stop rollers will oscillate the segmental members and said segmental members will each carry a nail 35 from its respective slot 36 and drop it into 35 its respective tubular conveyor 43. The conveyors 43 lead downwardly to discharge openings 15' in the nail receiving arm 15 which intersect hammer guide openings 44 also in said arm 15. The guide openings 44 are approximately of the same diameter as 40 the hammers 17 but slightly smaller than the heads of the nails so that when said nails enter the openings from the larger openings of the tubular conveyors 43 they will be held 45 at the points of intersections of the openings 15' with the openings 44. To permit the further downward movement of the nails a portion 43' of the arm 15, is yieldingly mounted by means of bolts and springs 44' 50 to give outwardly to increase the size of the openings 44 so that the hammers can force the nails therethrough and into the box part to be nailed while being guided by the arm 15.

55 A rock shaft 45 positioned in front of and carried by the upper frame part 14 has mounted thereon stop fingers 46 which are adapted to be swung upwardly into the path of movement of the arms 37' of the segmental members 37 when desired to stop the feed of nails to all or any number of the tubular conveyors 43. The shaft 45 is rocked at predetermined periods by means 60 of an arm 47 mounted on the shaft 45 and having a link and bell crank connection 48

with a cam 49 mounted on the shaft 25. As the gear 23 is about one half the diameter of the gear 24 the shaft 25 will only be rotated at half the speed of the shaft 22 with the result that the stop fingers 46 when locked 70 to the rock shaft will only be swung into the paths of movement of the arms 37' every other reciprocation of the arm 16, so that if one finger 46 is locked to the shaft the machine will alternately drive three nails and 75 then two nails at each stroke. Screws 46' are provided for locking the fingers to the shaft 45. While the machine as shown is adapted to drive three nails at each stroke it is to be understood that the parts may be 80 duplicated to drive any number of nails desired, that fingers may be adjusted to alternately drive different numbers of nails without departing from the spirit and scope of the invention. The link connection 48 may be disconnected and the arm 47 be turned by hand to stop the feed of nails to the tubular conveyors 44 or to any number of said conveyors. 85

In use if adjusted in the manner described, a box requiring three nails on each side and two nails on each end may be quickly nailed and the respective sides and ends of the box be alternately nailed automatically with the correct number of nails in each part. 90

From the foregoing description it will be seen that the nailing machine is of very simple construction and is well adapted for the purpose described. 95

What I claim as my invention is: 100

1. A nail feeding mechanism for a nailing machine provided with a plurality of nail drivers, comprising a plurality of nail raceways having offset portions; a nail feeding member comprising an oscillating disc associated with each of said raceways provided with a recess in its edge adapted to register alternately with the offset portions of said raceway, whereby a nail may be received therein from one portion and be moved to the other portion; resilient means for moving said feeding members in one direction; positive means for moving said members in the other direction; and hand set automatically operated means for preventing the functioning of said resilient means at predetermined intervals to stop the oscillations of certain of said feeding discs on alternate operations of said nail drivers. 110

2. In a nail feeding mechanism for nailing machines, a plurality of nail raceways having offset portions; an oscillating feeding disc operatively associated with each of said raceways to receive and transfer nails from one portion to the other thereof; an arm rigidly secured to each of said discs; a positively actuated slide bar for engaging and moving said arms and discs in one direction; spring means for moving said discs and arms in the other direction; a rock shaft; 120

125

and readily adjustable means carried by said rock shaft adapted to engage said arms and to prevent their movement under the influence of said springs.

5. 3. In a nail feeding mechanism for nailing machines, a plurality of nail raceways having offset portions; an oscillating feeding disc operatively associated with each of said raceways to receive and transfer nails from 10 one portion to the other thereof; an arm rigidly secured to each of said discs; a positively actuated slide bar for engaging and moving said arms and discs in one direction; spring means for moving said discs and arms in the other direction; a rock 15 shaft; and a plurality of sleeves each provided with a stop finger readily adjustably carried by said rock shaft, said fingers be-

ing adapted to engage said arms and to prevent their movement under the influence of 20 said springs.

4. In a nail feeding mechanism for nailing machines, a plurality of oscillating nail feeding members each provided with an arm; an adjustable stop carried by each of said 25 arms; a cam actuated slide bar provided with rollers adapted to coat with said stop members to move said arms in one direction; spring means for moving said arms in the other direction; a rock shaft; and adjustable 30 stop fingers carried by said rock shaft adapted to be moved into the paths of said arms to prevent their movement by said springs.

In testimony whereof, I affix my signature.

JOHN ALBRECHT.
